UNITED STATES PATENT OFFICE.

ALBERT T. WEISS, OF ROCHESTER, NEW YORK, ASSIGNOR TO YAWMAN & ERBE MFG. CO., OF ROCHESTER, NEW YORK, A CORPORATION OF NEW YORK.

FURNITURE-CASING.

1,186,634.

Specification of Letters Patent. Patented June 13, 1916.

Application filed January 26, 1914. Serial No. 814,408.

To all whom it may concern:

Be it known that I, ALBERT T. WEISS, of Rochester, in the county of Monroe and State of New York, have invented certain new and useful Improvements in Furniture-Casings; and I do hereby declare the following to be a full, clear, and exact description of the same, reference being had to the accompanying drawings, forming a part of this specification, and to the reference-numerals marked thereon.

My present invention relates to furniture and more particularly to metallic furniture of the type used in office and library, such as bookcases and filing cabinets, and it has for its object to provide a sheet metal casing or shell of simple and economical construction that can be assembled or knocked down with ease, the improvements being more particularly directed to the construction and mode of attachment of a lateral wall of the casing.

A further object of the invention is to fit such a casing for use as a sectional unit for the so-called "elastic" or sectional furniture.

To these and other ends the invention consists in certain improvements and combinations of parts, all as will be hereinafter more fully described, the novel features being pointed out in the claims at the end of the specification.

In the drawings: Figure 1 is a perspective view of a sheet metal casing constructed in accordance with and illustrating one embodiment of my invention, the point of view being rearward; Fig. 2 is a similar enlarged but fragmentary view showing the rear wall detached and with a portion of the end wall removed; Fig. 3 is a fragmentary perspective view of the back wall, the point of view being from the inside; Fig. 4 is a vertical sectional view taken from front to rear, substantially on the line 4-4 of Fig. 6; Fig. 5 is a fragmentary horizontal section taken through an end wall and part of the back wall; Fig. 6 is a vertical fragmentary section through an end wall taken substantially on the line 6-6 of Fig. 5, and Fig. 7 is a fragmentary top plan view of a corner of the casing.

Similar reference numerals throughout the several figures indicate the same parts.

I have illustrated my improvements in the present instance, as embodied in a sectional furniture unit of a shape known as a "horizontal unit" because of its greatest dimen-

sion being horizontal, which type is often used as a single book shelf; but it will be understood that the invention relates only to the shell and the interior may be fitted up as desired. In this view, 1 indicates the top wall, 2 the bottom wall and 3 the ends walls. The first mentioned or horizontal walls are both secured to the end walls, preferably by means of extensions or tongues 4 that extend through the latter and receive wedges 5 (Figs. 2 and 5) all of which is described in detail and claimed by me as a separate invention in another application filed January 26, 1914, Serial No. 814,407. The end walls have outstanding marginal flanges 6 covered by facing plates 7, secured by tie rods 8, as will also be disclosed in the said additional application.

At both front and rear, the bottom wall 2 is flanged downwardly at 9 and thence horizontally at 10 to constitute supporting elements so that the said wall is raised or spaced in the manner of a false bottom when the section is resting upon an adjoining section or surface.

The top wall is flanged upwardly at 11 at both its front and rear edges and thence horizontally or inwardly at 12 and upwardly again at 13 to constitute seats for the portions 9-10 of a similarly formed superposed section to rest upon and at the front this seat is preferably reinforced by an angle plate 14 welded or otherwise secured to the flange 13 and to the body of the wall 1. At the rear, the upstanding flange 13 is provided with a plurality of slots or openings 15 at its base in alignment with the bottom of the seat.

The rear wall consists of a plate 16 having a forwardly turned flange 17 at its bottom provided with upwardly turned portions 18 that constitute, at that edge of the wall, a grooved or hooked portion that is adapted to engage over and interlock with the flanges 9-10 of the bottom wall by an upward movement or one in the direction of the plane of the rear wall, and transversely of the top and bottom walls, as shown in Fig. 4. At its top edge, an inwardly or forwardly turned flange 19 has forwardly extending flat projections 20 which coöperate with the slots or openings 15 by a forward movement of the top edge of the back in a direction transversely to the plane of the latter and parallel with the

plane of the top wall while the flange 19 passes into the seat 12-13 and is interposed between the latter and the superposed section.

5. It will thus be seen that to apply the back it is only necessary to interlock it at the bottom by an upward movement and then swing the top edge forwardly. When the extensions 20 have passed through the slots 10 15 they may be secured in other ways so far as some features of my invention are concerned, but I prefer to give them a lateral twist, as clearly shown in Figs. 4 and 6, as this is a simple operation and at the same 15 time tends to draw the parts more closely together.

A lining wall 21 having offset flanges 22 at top and bottom may be applied to the back wall with the said flanges held between 20 the latter and the flanges 9 and 11, as shown in Fig. 4, and a filling 23 of heat insulating material supplied between the wall and its lining.

The ends of the back wall are preferably 25 turned inwardly at 24 and thence flanged laterally at 25 which last mentioned flanges are secured between the flanges of the end walls 3 and their facing plates 7, as will be dealt with in the said additional application 30 heretofore mentioned.

I claim as my invention:

1. In a metallic furniture casing, the combination with a wall provided with an outwardly projecting marginal flange having 35 openings therein, of an adjoining wall co-operating therewith and having an inwardly turned flange parallel with the first mentioned wall provided with extensions passing through the openings in said first mentioned flange and secured therein.

2. In a metallic furniture casing, the combination with a wall having a marginal flange thereon proceeding outwardly and thence inwardly parallel with the wall and thence 45 outwardly again, said last mentioned portion being provided with slots, of an adjoining wall co-operating therewith and having an inwardly turned flange superposed upon the said inwardly turned portion of the first 50 mentioned flange and provided with extensions passing through the slots in the latter and secured therein.

3. In a metallic furniture casing for sectional furniture, the combination with a 55 horizontal wall having a marginal flange turned vertically and thence inwardly in a horizontal direction and thence vertically

again to provide a seat for the wall of an adjoining section, said seat being spaced from its said carrying wall.

4. In a metallic furniture casing for sectional furniture, the combination with a horizontal wall having a marginal flange turned vertically and thence inwardly in a horizontal direction and thence vertically 65 again to provide a seat for the wall of an adjoining section, said seat being spaced from its carrying wall and its vertically turned portion being provided with openings, of an adjoining wall having an inwardly turned 70 flange disposed flat against the horizontal portion of the seat and provided with extensions passing through the openings in the vertical portion and secured therein.

5. In a metallic furniture casing, the combination with two opposite parallel walls respectively provided with outwardly projecting marginal flanges, one of which has openings therein, of an intermediate wall having a flange at one side adapted to interlock with that on the other of said first mentioned walls by a lateral movement in a direction in the plane of said intermediate wall and having inwardly projecting extensions at the other side adapted to enter the openings in the flange of the opposite wall by an inward movement in a direction transversely of the plane of the intermediate wall and to be secured therein.

6. In a metallic furniture casing, the combination with two opposite parallel walls respectively provided with outwardly projecting marginal flanges, one of which proceeds outwardly and thence inwardly and finally outwardly again, the last mentioned 95 portion being provided with openings, of an intermediate wall having a flange at one side adapted to interlock with that on the other of said first mentioned walls by a lateral movement in a direction in the plane of said 100 intermediate wall and an inwardly projecting flange at the other side arranged to lie against the inwardly proceeding portion of the flange of the opposite wall and provided with extensions adapted to enter the 105 openings in the adjacent portion of said flange by an inward movement in a direction transversely of the plane of the intermediate wall and to be secured therein.

ALBERT T. WEISS.
